UNITED STATES PATENT OFFICE.

GEORGE LYTTON SEXTON, OF WAUKESHA, WISCONSIN, ASSIGNOR TO THE BADGER CONCRETE MIXER AND MACHINERY CO.

PORTABLE CONCRETE-MIXER.

1,108,523.

Specification of Letters Patent. Patented Aug. 25, 1914.

Application filed January 29, 1913. Serial No. 745,061.

To all whom it may concern:

Be it known that I, GEORGE LYTTON SEXTON, a citizen of the United States, residing at Waukesha, in the county of Waukesha, State of Wisconsin, have invented certain new and useful Improvements in Portable Concrete-Mixers, of which the following is a specification.

My invention relates to the construction of a concrete mixer, whereby many advantages are obtained not possible with concrete mixers heretofore in use. Among the advantages are that the mixer is portable, and owing to its size, shape and construction, may be readily moved from point to point without requiring the exhibition of any considerable effort on the part of the mover. The mixing drum is arranged near to the earth, and is adapted to receive the materials to be mixed at the rear, and to discharge them from the front end. The motive power which turns the mixer is mounted over the drum in a position where it will not be subjected to the destructive action of flying dust.

My invention embodies various details of construction which will be described in the specification, and specifically pointed out in the claim.

The accompanying drawings will serve to illustrate my invention, in which—

Figure 1 is a side elevation of the portable mixer; also showing in dotted lines, the position occupied by the mixer when tilted to move it from place to place. Fig. 2 is a view, partially in elevation, taken on the line II—II of Fig. 3 and looking from the left. Fig. 3 is a view, partially in elevation, taken substantially on the line III—III of Fig. 2.

In the drawings, 5 represents a carriage frame, which is made up of the longitudinal and transverse channel irons 6—7. At the rear end of the carriage frame is a handle bar 8, and at the forward end, an axle 9 on which are mounted the wheels 10.

Secured to the channel iron 6 at the rear of the carriage frame, are skidding shoes 11. The forward portion of the skidding shoes is carried upward to form a brace 12. Located on the forward part of the channel iron 6, is a frame 13, which consists of four vertical members 14 and four horizontally disposed channel irons 15. The frame 13 is substantially rectangular. Located below the channel irons 15, and secured and mount-

ed in bearings 16, secured to the channel irons 7, are shafts 17, on which are mounted flange rollers 18. There are two shafts and four rollers. The tops of the flange rollers 18, it will be seen by reference to the figures, 30 are located below the top of the channel irons 7. Mounted on the rollers is a mixing drum 19, which is preferably made of steel cast in two halves, joined together at the center in any suitable manner. On the exterior of the drum and corresponding in position with the flange rollers 18, are raised trackers 20. Located on the interior of the drum and at the rear of the drum, are a series of concave blades or scoops 21. These 65 blades are inclined downwardly from the back of the drum toward the front of the drum. Located in the front of the drum and alternately disposed as regards the blades, are a series of buckets 22. Arranged in the back of the drum and in the front of the drum are openings 23—24. Secured to the braces 12 by means of an angle iron 25, is an inclined hopper 26, the forward end of which projects into the drum through the 70 opening 23. Mounted on an arm 27, pivotally supported on the forward vertical members 14 of the frame 13, is a discharge spout 28, and secured to one of the horizontal members 15 of the frame 13, are hooks 29, 75 adapted to engage with the upper end of the arm 27 to hold the discharge spout in the position shown in Fig. 1. The two positions which the spout may occupy are respectively shown in Figs. 1 and 2. The braces 12 are 80 connected to the rear vertical members 14 of the frame 13 by plates 30 or otherwise, the braces 12 serving to stiffen the frame 13. Located on the top and at the rear of the frame 13, is a motive power device, shown as 85 a gas engine. Manifestly any suitable motive power device may be employed. Situated on the exterior of the drum and over the joint between the two halves of the drum 90 19, is a segmental tooth driving ring 31. Located on the top and at the rear of the frame 13, is a motive power device, shown as 95 a gas engine. Manifestly any suitable motive power device may be employed. Situated on the exterior of the drum and over the joint between the two halves of the drum 19, is a segmental tooth driving ring 31. Located on the top and at the rear of the frame 13, is a motive power device, shown as 100 a gas engine. Manifestly any suitable motive power device may be employed. Situated on the exterior of the drum and over the joint between the two halves of the drum 19, is a segmental tooth driving ring 31. Located on the top and at the rear of the frame 13, is a motive power device, shown as 105 a gas engine. Manifestly any suitable motive power device may be employed. Situated on the exterior of the drum and over the joint between the two halves of the drum 19, is a segmental tooth driving ring 31. Located on the top and at the rear of the frame 13, is a motive power device, shown as 110 a gas engine. Manifestly any suitable motive power device may be employed. Situated on the exterior of the drum and over the joint between the two halves of the drum 19, is a segmental tooth driving ring 31.

It will be observed that the motive power device is located at the rear of the frame 13, the object of which arrangement is to pro-

vide that when the carriage frame 5 is lifted to the position shown in dotted lines in Fig. 1, the weight of the motive power device shall be located over the driving axle, and 5 thus provide that the operator shall not be obliged to support any portion of the weight of the apparatus in moving it from point to point.

The operation of my improved mixer will 10 be readily understood. The material to be mixed is introduced through the hopper 26 (the delivery spout having first been moved to the position shown in Fig. 1) and falls to the bottom of the drum. As the drum is 15 rotated, the concave blades 21 lift the material and throw it toward the front end of the drum and into the buckets 22, from whence it is discharged again into the bottom of the drum as the drum revolves. After mixing is 20 effected, the discharge spout is thrown into the position shown in Fig. 3. When in this position the material discharged into the buckets 22 is by them discharged through the spout upon the ground into a wheel-barrow 25 or other receptacle provided for the purpose but not shown.

I wish it understood that I do not limit myself to the specific means described for mounting the drum upon the carriage frame, or for transmitting the power to the drum, 30 as it will be obvious that these features of construction may be modified without departing from the intent of my invention.

Having thus described my invention, I 35 claim;

In a portable concrete mixer, a suitable running gear, a mixer mounted thereon, a frame carried by said running gear, and a motive power device mounted upon said frame in such a position that the center of gravity of the device will be shifted from its position without the vertical plane of the axle to a position substantially within said plane when the device is in position for 40 translation.

45 In testimony whereof, I affix my signature, in the presence of two witnesses.

GEORGE LYTTON SEXTON.
